UNITED STATES PATENT OFFICE.

WILHELM GÖMANN, OF BROOKLYN, NEW YORK.

BEER-PIPE-CLEANING MACHINE.

No. 917,286.

Specification of Letters Patent.

Patented April 6, 1909.

Application filed October 8, 1908. Serial No. 456,844.

To all whom it may concern:

Be it known that I, WILHELM GÖMANN, a subject of the Emperor of Germany, residing at Brooklyn, in the county of Kings and 5 State of New York, have invented certain new and useful Improvements in Beer-Pipe-Cleaning Machines, of which the following is a specification.

The present invention relates to beer-pipe 10 cleaning machines, and has for its object to provide a machine of a simplified construction and which is lighter than those hitherto used for the same purpose.

Another object of my invention is to equip 15 the machine with an atomizer which will allow of the chemical solution used for the cleaning to mix more thoroughly with the water before it is sent through the beer pipes. Owing to this thorough mixing of the solution 20 with the water, the beer pipes will be cleaned uniformly at all points. With the hitherto used machines, it is found, that because of the failure of thoroughly mixing the solution with the water, the cleaning is imperfect. 25

To make my invention more clear the same is illustrated in the accompanying drawings in which similar reference letters denote corresponding parts and in which—

30 Figures 1 and 2 are elevations of the machine seen from sides at right angles to one another.

In the drawing, *a* denotes a receptacle having a vaulted top *b*, a vaulted bottom *c* and a 35 similarly shaped cross partition *d*. The latter divides the receptacle into two compartments *e* and *f*, of which the upper compartment *e* serves as a compressed air vessel, and the lower compartment *f* as a receptacle for 40 the chemical solution which consists of 50% antiformin, 40% salt and 10% soda.

g is a manometer and *h* a supply opening for the solution, the latter being adapted to be closed by a cap or the like.

45 On the outside of the top *b* of the receptacle *a* a vessel *i* is provided, which has an air valve *j* and inside two or more perforated pipes *k* and *l*. The latter form the atomizer for the chemical solution. Terminating in 50 the vessel at one side is a pipe *m* having a valve or cock *m'* and which is adapted to be connected with the water supply pipe (not shown). Communicating with the said pipe *m* at the rear of the valve *m'* is a pipe *n* rising 55 from the air vessel *e* and having a valve or cock *n'*. With the other side of the recepta-

cle *i* communicates a pipe *o* having a valve *o'* and adapted to be connected by a hose *o''* with the beer pipes to be cleaned (not shown).

Rising vertically from the solution receptacle *f* through the air vessel *e* into the vessel *i* is a pipe *p* having at its upper end a valve or cock *p'*.

To the outside of the receptacle *a* an air pump *q* of suitable construction is secured, 65 the lower end of said pump being connected to the air vessel *e* by a pipe *q'* which has a cock or valve *q''*. The attachment of the pump is accomplished by ring-shaped braces *r* screwed into blocks *s* attached to the receptacle *a* and having clamping rings *s* engaging the blocks *s'*. 70

The mode of operation is as follows:— After the air of about one hundred pounds is 75 pressed into the air vessel by means of the pump *q* and the compartment *f* is filled with the chemical solution, the hose *o''* leading from one or two coupled beer pipes is connected to the pipe *o*. The valves *m'* and *o'* are opened and water from the supply is sent 80 through the beer pipes to effect a preliminary cleansing. Thereupon the valve *n'* is opened, all other valves, save valve *o'*, being closed, permitting compressed air from the air vessel *e* to rush through the vessel *i* and the 85 beer pipes, whereby the rest of the water that may have remained in the vessel and the pipes is ejected. The valve *p'* is then opened

90 after closing valve *o'* to permit compressed air to enter through valve *n'*, and the vessel *i* into pipe *p* and through the latter into the solution receptacle *f*, in which it rises in form of bubbles through the solution to the top *d* of the chamber. When the valve *n'* is closed and the air valve *j* opened, the solution, owing to the high pressure of the air contained in the vessel *f*, will be forced upward through the pipe *p* into the vessel *i*, in which, by the perforated pipes *k*, *l*, it will be atomized. Simultaneously the valves *p'* 95 and *j* will be closed and valves *m'* and *o'* opened, which will permit the water to rush into the vessel *i* and, mixing with the atomized chemical solution, to pass through pipe *o*, valve *o'*, hose *o''* through the beer pipes to 100 be cleaned.

105 It is understood that some modifications may be made in the various parts of the construction without deviating from the spirit of my invention.

110 What I claim and desire to secure by Letters Patent is:—

1. A beer-pipe cleaning machine, comprising an air pump, a receptacle divided into an upper vessel communicating with said air pump and a lower vessel to contain the 5 chemical solution, an outer vessel, a valve-controlled pipe leading from the solution compartment into said outer vessel, a valve-controlled pipe for connecting the latter with a water supply, a valve-controlled pipe for connecting the outer vessel with the beer pipes to be cleaned, a valve connection between the air vessel and the outer vessel and an air valve in the latter.

2. A beer-pipe cleaning machine, comprising 15 an air pump, a receptacle divided into an upper vessel communicating with said air pump and a lower vessel to contain the chemical solution, an outer vessel, an atomizer in the latter, a valve-controlled pipe leading 20 from the solution compartment into said outer vessel, a valve-controlled pipe for connecting the latter with a water supply, a valve-controlled pipe for connecting the

outer vessel with the beer pipes to be cleaned, a valve connection between the air vessel and the outer vessel and an air valve in the latter. 25

3. A beer-pipe cleaning machine, comprising an air pump, a receptacle divided into an upper vessel communicating with said air pump and a lower vessel to contain the chemical solution, an outer vessel, perforated pipes 30 in the latter forming an atomizer, a valve-controlled pipe leading from the solution compartment into said outer vessel, a valve-controlled pipe for connecting the latter with a water supply, a valve-controlled pipe for connecting the outer vessel with the beer 35 pipes to be cleaned, a valve connection between the air vessel and the outer vessel and an air valve in the latter. 40

In testimony whereof I affix my signature in presence of two witnesses.

WILHELM GÖMANN.
